United States Patent Office.

HARLOW GILSON AND CHARLES F. SOUTHWICK, OF NASHUA, NEW HAMPSHIRE.

Design No. 4,962, dated May 30, 1871.

DESIGN FOR A BRACKET.

The Schedule referred to in these Letters Patent and making part of the same.

We, HARLOW GILSON and CHARLES F. SOUTHWICK, of Nashua, county of Hillsborough and State of New Hampshire, have invented and produced a new and original Design for Brackets, of which the following is a specification.

The nature of our design is fully represented in the accompanying drawing, to which reference is made.

We claim as our invention—
The design for a bracket, as shown.
HARLOW GILSON.
CHARLES F. SOUTHWICK.
